METHOD OF MAKING SHAFTS

Joseph E. McLaughlin, Arnold, Pa., assignor to
 Aluminum Company of America, Pittsburgh,
 Pa., a corporation of Pennsylvania

Application April 18, 1933, Serial No. 666,697

5 Claims. (Cl. 29—156)

The invention relates to a method of fabricating shafts of novel cross sectional configuration from previously formed seamless tubing. More particularly, it concerns the production of a shaft of seamless convoluted tubing characterized by increased resistance to transverse bending, combined with decreased resistance in torsion.

The special tubing produced by my novel method finds particular application in the manufacture of shafts for sporting goods, as exemplified by golf club shafts. For a considerable number of years efforts on the part of inventors and manufacturers alike have been directed toward the problem of producing a tubular metal shaft for golf clubs which would possess as nearly as possible the desirable characteristics of a wood shaft. Probably the most serious difficulty which has been encountered in the attempt to produce a metal shafted club which would have something of the same "feel" as a wood shafted club is that of obtaining the desired torsional characteristics. It is a well known fact that the usual metal shafted club which is produced from a tapered or stepped tubing, usually of simple circular cross section, does not have the feel of a wood shaft and does not "whip" at the moment of impact with the ball in the manner of a wood shafted club. This disadvantage of the metal shaft has generally been ascribed to the fact that the torsional rigidity of the metal shaft is too high. Yet, it has not been considered feasible to decrease the torsional rigidity to the desired point without too great a sacrifice of bending strength. As a consequence, those golfers who wish to use metal shafted clubs have been compelled to adjust themselves to the different feel of the club, and it is claimed by many that the lack of proper torsional characteristics diminishes the distance of the drive which can be made with a given type of club.

It is, therefore, an object of this invention to provide a form of metal shaft which possesses the desired torsional characteristics, having an increased bending moment as compared with ordinary tubing of like size and material, yet having less torsional rigidity than that possessed by ordinary tubing.

More broadly, it is an object of my invention to provide a method of fabricating a seamless tube of novel cross sectional configuration which is characterized by a smooth cylindrical outer surface and portions folded inwardly toward the center, with the inwardly folded portions preferably meeting adjacent the center of the tube. The invention has been developed with reference to

the formation of shafts of aluminum, and it has been found that this metal is particularly well adapted to fabrication in accordance with the method herein described. Other objects and advantages will appear from the following description when taken in connection with the accompanying drawings.

In the drawings Fig. 1 is a diagrammatic view in central vertical cross section illustrating the method of drawing a previously formed polygonal tube through a series of circular die openings provided with flaring entrance portions. Fig. 2 is an end view of the polygonal tube. Fig. 3 is an end view of the finished shaft. Fig. 4 is an enlarged cross section of the partially formed tube taken on the line IV—IV of Fig. 1; and Fig. 5 shows a similar cross section at a more advanced stage of the forming operation taken on the line V—V of Fig. 1. Fig. 6 represents an elevational view of a completed shaft of stepped formation.

Fig. 7 is an isometric view partially in central vertical cross section illustrating an alternative method which comprises drawing a previously formed polygonal tube through a single die block provided with a circular die opening having a long flaring entrance portion.

Fig. 8 illustrates a modified form of apparatus which may be used to carry out the method indicated in connection with Figs. 1 and 7.

Figs. 9 to 12, inclusive, are elevational views with cross sectional views appurtenant, illustrating a further modification of my invention. Fig. 9 is an elevational view of a round tube. Fig. 10 is a similar view with cross sectional views appurtenant showing the form of the shaft at the conclusion of the first step of the modified method. Fig. 11 is a similar view with cross sectional views appurtenant showing the form of the shaft at the conclusion of the second step of the modified method; and Fig. 12 is a similar view with cross sectional views appurtenant of the finished shaft as produced in accordance with this modified method. Fig. 13 is a fragmentary view in central vertical cross section showing to a somewhat enlarged scale the formation of the shaft of Fig. 12 at the point where the convoluted portion thereof blends into a portion of regular circular cross section.

There is shown in Fig. 1 a series of die blocks 1, 2, and 3, which are provided with circular openings 4, 5, and 6 respectively. The diameter of the circular opening 6 of die 3 corresponds to that of the shaft which is to be produced. The entrance portion of each die opening is flared

outwardly as indicated at 7 in die block 1. The particular shape of the flaring portion 7 is subject to some variation, but I prefer that it be substantially cone shaped, with the surface of 5 the cone at an angle of approximately 10° to the axis thereof. At its widest portion it should be slightly greater in diameter than the diameter or longest transverse dimension of the tube which is to be introduced.

10 As indicated in Fig. 1, the shape of the flaring opening 7 at the entering face of the die 1 is substantially circular. However, this may be varied to conform more or less with the shape of the previously formed tube which is to be drawn. 15 Furthermore, if the flared entrance to the die 1 is made of suitable polygonal shape, preforming of the tube to a polygonal shape may be eliminated and a plain circular tube can be fed into the die block 1. Again, it is not strictly necessary 20 that the exit portions 4 and 5 of the die blocks 1 and 2, respectively, be circular. It is an essential feature, irrespective of the shape of the openings of the die blocks 1 and 2 or of the shape of the entrance portion 8 of the die block 3, that 25 the exit portion 6 of the die block 3 be substantially circular or curvilinear in cross section. I have found that if a polygonally shaped tube, such as a tube which is hexagonal or octagonal in cross section, is drawn through a die opening or 30 series of die openings which, at the narrowest point, is substantially circular, it is possible to produce a shaft of unique cross section. The shaft so produced (Fig. 3) is characterized by inwardly folded portions 9 and a smooth cylindrical outer surface 10. The form of the shaft will be more fully described below in connection 35 with Fig. 7. The shaft is further characterized by the sharp line contact 11 at the outer surface 10 of the tube, the relationship between the outside perimeter of the previously formed 40 polygonal tube 12 to the circumference of the exit portion 6 of the die 3 being such that the meeting edges of the folds 9 are forced so tightly together as to form sharp corners which blend 45 smoothly into the outer cylindrical surface 10 of the shaft.

It is also possible, through selecting the proper size of die opening 6 for a given size of polygonal tube 12, to force the inwardly folded portions 9 50 together until they meet adjacent the center of the shaft, as shown in Fig. 3. The folds so produced serve to increase the transverse bending strength of the shaft, and yet, by reason of the fact that the openings between each fold face 55 outwardly, they make possible a certain amount of "give" in torsion. The "give" is retarded to a certain extent by the frictional engagement between the walls of the fold, and by regulating the area of contact between the folds it is possible 60 to vary the torsional resistance within certain limits.

It will, of course, be understood that instead of the octagonal tube 12 shown in Fig. 2, it is possible to use a previously formed tube having a 65 greater or less number of sides. If a hexagonal tube is used, there will be produced three double folds instead of the four indicated in Fig. 3. In the case of a square tube there would be produced two double folds. It is also not strictly 70 necessary that the sides of the polygon be flat, because if the previously formed tube were of a cross section such as indicated in Figs. 4 or 5, for instance, it would still be possible to produce a shaft of the desired configuration. It should, 75 therefore, be understood that the term "polyg-

onal" as used herein is intended to include such substantially polygonal structures as indicated in Figs. 4 or 5. The gist of the method consists in subjecting the tube to collapsing pressure, which pressure is applied at predetermined points—this predetermination being governed by the shape of the polygonal tube itself—whereby the walls of the tube are caused to collapse inwardly, and continuing to reduce the circumference of the partially collapsed tube by progressively contracting the circle of application of pressure with respect to the axis of the tube until the edges of the inwardly collapsed portions meet to form a smooth cylindrical outer surface on the finished tubing. This result may be accomplished through 10 the medium of a series of die blocks such as has been described with reference to Fig. 1; or it may be accomplished by means of a single die block such as illustrated at 13 in Fig. 7.

In connection with Fig. 7, it will be noted that 20 Fig. 4 of the drawings, which has previously been described as a section taken on the line IV—IV of Fig. 1, also shows the cross section of the partially formed tube taken on a line represented at IV—IV of Fig. 7; and Fig. 5 shows a similar cross 25 section at a more advanced stage of the forming operation, as represented by the plane V—V of Fig. 7. The general concept of the invention and the exact form of the shaft produced are clearly illustrated in Fig. 7. The die block 13 is provided 30 with a substantially circular opening 14 and a flaring entrance portion 15. The circular opening 14 corresponds in diameter to the diameter of the shaft which is to be produced. The particular shape of the flaring portion 15 is subject 35 to some variation, but, as was said in connection with a description of the flaring opening 7 of the die block 1 of Fig. 1, I prefer that it be substantially cone shaped. At its widest portion it should be slightly greater in diameter than the diameter 40 or longest transverse dimension of the tube 12' which is to be introduced.

Also parallel to the description of Fig. 1 and still with reference to the particular disclosure of Fig. 7, it is to be noted that the circular form 45 of the entering face of the flaring opening 15 may be varied to conform more or less with the shape of the previously formed tube which is to be drawn; and if the flared entrance 15 be of suitable polygonal shape, preforming of the tube 50 to a polygonal shape may be eliminated so that a plain circular tube can be fed into the die block 13. Whatever the shape of the entrance portion 15, it is an essential feature that the exit portion 14 of the die be substantially circular or 55 curvilinear (it may be elliptical) in cross section. The method illustrated by Fig. 7 is essentially the same method as that illustrated by Fig. 1. The shaft produced is characterized by inwardly folded portions 9' and a smooth cylindrical outer 60 surface 10'. The outwardly facing opening 16 between each fold 9' is tightly closed at the outer surface 10' of the tube, the relationship between the outside perimeter of the previously formed polygonal tube 12' to the circumference of the 65 exit portion 14 of the die being such that the meeting edges of the folds 9' are forced so tightly together as to form sharp corners 17 which blend smoothly into the outer cylindrical surface 10' of the shaft. It is also possible, through selecting the proper size of die opening 14 for a given size of polygonal tube 12', to force the inwardly folded portions 9' together until they meet adjacent the center of the shaft as at 18.

It has now been seen that the shaft just de- 75

scribed may be produced by means of a series of die blocks as shown in Fig. 1 or by means of a single die block as shown in Fig. 7. A further modification is shown in Fig. 8, in which pattern rolls are shown in place of dies. In so far as die drawing and die rolling produce equivalent results, they are to be considered as equivalents in the definition of the present invention. It is, therefore, intended that wherever the term "die" is used, it will in its full signification include not only a simple die but also a die which is made up of pattern rolls.

The meeting portions of a set of pattern rolls are shown at 19 in Fig. 8. These pattern rolls are made to form a circular opening 20. The method here indicated is generally referred to as die rolling, as contradistinguished from die drawing.

The finished shaft may be further reduced by drawing through a series of dies in order to form a shaft of the form shown in Fig. 6. Again, the finished shaft may be tapered by means of any of the well known apparatus for producing tapered shafts. In either the tapered or the stepped form of shaft it is possible to so proportion the size of the previously formed polygonal tube and the size of the finished shaft that the inwardly folded portion 9 or 9' will meet in tight pressed engagement at the smaller end of the shaft but be slightly separated at the larger end, while throughout the entire length of the shaft the desired smooth cylindrical outer surface is maintained. The finished shaft, as described in connection with Fig. 7, may be further processed by drawing it through another die to give it a square shape or the shape of a square with rounded corners. In this event, the line of contact 11' between the meeting edges of the folds 9' at the surface of the shaft will preferably be disposed at the corners of the square. That is to say, I contemplate further processing of the shaft by passing it through a polygonal die which would serve to flatten the outer walls of the shaft between the folds, while maintaining the sharp line contact between the meeting edges 11 of the folds where they blend into the outer surface of the shaft.

Reference is now had to the modification illustrated in Figs. 9 to 13, inclusive. This modification shows the possibility of localizing and controlling the torsional characteristics in a shaft fabricated in accordance with my process. If, for instance, it should be found desirable to decrease the torsional resistance of a golf club shaft near the head of the club, while leaving the remainder of the shaft more rigid in torsion, or to effect the decrease in torsional resistance near the grip or elsewhere, this can readily be accomplished by means of the method here indicated. A round tube of suitable diameter (Fig. 9) is drawn into steps 21, 22, and 23 of varying diameter proportioned and arranged in accordance with the length of that section of the shaft which is to be provided with reentrant folded portions in accordance with the method already described. The portion 22 of the tube is left at a diameter larger than that of the other portions and is drawn through a die to give it an octagonal or other suitable polygonal shape in accordance with any of the methods which are now known to the art for accomplishing this purpose. This step of the process produces a shaft of the form shown in Fig. 10, having a portion of its length polygonal in cross section as at 22, and having

other portions of its length substantially circular in cross section as at 21 and 23.

The shaft of Fig. 10 is then drawn through a circular die or a series of circular dies such as shown in Fig. 7 and Fig. 1, the exit portion of the die or of the final die being of such size that reentrant portions are formed and folded together in the portion 22' of the shaft as indicated in Fig. 11. The shaft is then tapered or step drawn over its entire length and trimmed to give it the desired final form. Fig. 12 shows a tapered shaft. Fig. 13 shows the cross sectional configuration of the shaft at the point where (in Fig. 12) the convoluted portion 22'' of the shaft joins the simple circular section 23''. It will be seen that the outer surface of the shaft is perfectly smooth and unbroken at the juncture between the two sections. Upon close inspection of the shaft produced in accordance with this particular method, a fine line is discernible at the meeting edges of the folds, as at 24 in Fig. 12. This line 24 blends into and disappears at the beginning of the circular portions 21'' and 23'' of the shaft. The completed shaft as shown in Fig. 12 is thus provided with a portion 21'' which is quite rigid in torsion, a portion 22'' of decreased torsional resistance, and a portion 23'' which, like the portion 21'', is relatively stiff in torsion. It is a feature of my invention, on the other hand, that the bending strength of the portion 22'' is high. This means that by my method it is possible to produce a shaft which, while strong, is yet sufficiently resilient to give the characteristics desired in a shaft for golf clubs and the like.

I claim:

1. The method of producing convoluted tubing having a smooth cylindrical outer surface which comprises subjecting a previously formed polygonally shaped tube to radial pressure effective initially only at corners of the polygon, the points of application of pressure lying in a plane perpendicular to the axis of said tube and approximately defining the circumference of a circle, whereby the walls of said tube are caused to collapse inwardly at predetermined points, and continuing to reduce the circumference of the partially collapsed tube by progressively contracting the circle of application of pressure with respect to the axis of said tube until the edges of the inwardly collapsed portions meet to form a smooth cylindrical outer surface on the finished tubing.

2. The method of producing convoluted tubing having a smooth cylindrical outer surface which comprises passing a polygonally shaped tube through a substantially circular opening the circumference of which is appreciably less than the perimeter of said polygonally shaped tube whereby the walls of said tube are caused to collapse inwardly at predetermined points, and continuing to reduce the circumference of the partially collapsed tube by passing it through openings of progressively smaller circumference until the edges of the inwardly collapsed portions meet to form a smooth cylindrical outer surface on the finished tubing.

3. The method of producing shafts for golf clubs and the like which comprises forming a tube which for a portion of its length is substantially circular in cross section and which for another portion of its length is polygonal in cross section, subjecting the polygonally shaped portion to radial pressure effective initially only at corners of the polygon, the points of applica-

- tion of pressure lying in a plane perpendicular to the axis of said tube and approximately defining the circumference of a circle, whereby the walls of said tube are caused to collapse inwardly at predetermined points, and continuing to reduce the circumference of the partially collapsed tube by progressively contracting the circle of application of pressure with respect to the axis of said tube until the edges of the inwardly collapsed portions meet to form a smooth cylindrical outer surface blending into the outer surface of said other portion of the tube which is substantially circular in cross section.
4. The method of producing shafts for golf clubs and the like which comprises forming a tube which for a portion of its length is substantially circular in cross section and which for another portion of its length is polygonal in cross section, passing the polygonally shaped portion of the tube through a substantially circular opening, the circumference of which is appre-
- 5
- 10
- 15
- 20

ciably less than the perimeter of said polygonally shaped portion, whereby the walls of said tube are caused to collapse inwardly at predetermined points, and continuing reducing the circumference of the partially collapsed portion of the tube by passing it through openings of progressively smaller circumference until the edges of the inwardly collapsed portions meet to form a smooth cylindrical outer surface blended into the outer surface of said first named portion of said tube.

5. The method of producing convoluted tubing having a smooth outer surface which comprises subjecting a polygonally shaped tube to pressure effective initially only on the corners of the polygon, and progressively decreasing the diameters of said tube to collapse the sides of said polygon inwardly until the edges of the collapsed portion meet to form a smooth outer surface on the tube.

JOSEPH E. McLAUGHLIN.
